ADJUSTABLE TEMPLATE

Erik E. Frisk, Duluth, Minn.

Application May 14, 1951, Serial No. 226,211

2 Claims. (Cl. 33—175)

1

This invention relates to an adjustable template, particularly adapted for use in repairing automobile bodies and the like.

In the repair of wrecked auto bodies a big problem is present. It is a difficult and very tedious job to bring the body back to its original shape and contour. This is particularly true if both sides of the body are dented, and if the roof is caved in, as there is no pattern for the body repairman to go by in his work. He must guess and judge when he has substantially the original shape returned to the body. If only one side of the body is dented, the repairman usually will take a piece of stiff paper or the like and, by the cut and try method, he will make a crude template from the undamaged side of the car and use it to give an indication of the correct contour for the repair of the damaged side. These templates, of course, are only good for one given point on a body, and a new template must be made for each different reading or pattern desired. Because of the tedious work required in making these cut templates, the number of templates made and used are few, as they add materially to the cost of the repair work.

There have been many adjustable contour meters invented and patented; however, these patented devices have not come into common use, at all, and are not used at present in the auto body repair work. These devices have certain structural or functional limitations and disadvantages, some of which are as follows: they are too bulky, too expensive to manufacture, too inconvenient to handle, they cannot easily be formed to a given contour without having such contour available to provide the impression, and they are not versatile.

It is, therefore, one of my principal objects to provide an adjustable template for use in auto body repair work and the like which is very versatile and convenient to use, whereby repair costs may be reduced materially and workmanship may be improved materially.

Another object is to provide an adjustable template which will be relatively inexpensive to manufacture and sell, and which will not be bulky or inconvenient to handle.

Another more specific object is to provide an adjustable template having a plurality of reciprocable fingers which are normally biased in an outward position, whereby the device may be readily "cocked" or set for taking a contour impression in a most convenient manner.

Another object is to provide individual locking means for each of the fingers, whereby they may

be locked into any desired adjusted position individually.

Still another object is to provide means to release all of said locking means simultaneously to "cock" or set the device for taking a contour impression.

Another object is to provide means for releasing each of said locking means individually if desired.

10 Another object is to provide graduations on each of the fingers, whereby a chart may be provided on which the relative reciprocable settings of each of the fingers are listed for a contour setting for certain given points on a given car make and model, thereby making it possible to set the template to a given contour from a chart when a pattern is not available, for example, when both sides of a body are damaged.

20 Another object is to provide means for pivotally connecting two of my templates together, whereby contours in angular relation to each other may be measured or set in their exact relation to each other.

25 These and other objects and advantages will become more apparent as the description of the invention proceeds.

In the accompanying drawing forming a part of this invention:

Figure 1 is a broken side elevational view, partly in section, showing two of my templates secured in end to end relationship.

30 Figure 2 is a perspective view illustrating one use of my invention.

Figure 3 is a side elevational view of an automobile door showing how my templates may be used to advantage.

Figure 4 is an enlarged view showing the interior construction of the invention.

Figure 5 is a sectional view on the line 5—5, Figure 4, with the body assembled.

40 Figure 6 is an enlarged end view of the hinge for connecting two of my templates.

In the drawings, the reference numerals 1—2 indicate the body member of my device, which is preferably made in two parts, 1 and 2, which are placed in abutting relation and secured together by screws, bolts, or the like, as shown.

50 The body member 1—2 is hollowed out, or chambered, as at 3, to receive the fingers 4, the chambers 3 and fingers 4 being preferably positioned equidistant apart along the length of the body, preferably about one to one and one-half inches apart. The chambers 3 extend from one edge 5 of the body through the body and the 55 opposite edge 6 thereof, and preferably have a

sheet metal liner 7 mounted therein so that a snug mounting is provided for the fingers, whereby the fingers may reciprocate freely in the lined chambers at all times as desired.

The fingers 4 are preferably hollow, as at 8, to receive one end of an expansive spring 9 which biases the finger in an outward position at all times, the opposite end of the spring 9 being butted against a closure strip 10 which extends along the edge 6 of the body 1-2 and closes one end of all the chambers 3, as shown. The inner end of the fingers have a projection or lug 11 thereon which serves to limit the distance to which the fingers may be extended from the body member, a stop 12 for the lug 11 being provided on the liner 7 to establish the desired limit to which the fingers may be extended.

As will readily be seen, all of the fingers will normally be held in their outermost extended position. It is desired, however, to lock some or all of the fingers in some partially extended position, according to a contour or immersion to be taken or made. To accomplish this end, I have provided a chamber 13 which communicates with and extends laterally from each of the chambers 3 adjacent the edge 5 of the body 1-2, the chambers 13 preferably being provided with a liner 14 which is a part of the liner 7 of the chamber 13, as shown. Within each of the chambers 13 a cam 15 is pivotally mounted, as at 16, the cam being biased by a spring 17 into engagement with the finger 4, as at 18. The surface of the cam which engages the cam is preferably provided with a friction facing 19, such as rubber, so that it will firmly frictionally engage the finger and hold it in place, it being noted that the cams 15 are so placed and so biased that the surface 19 is constantly against the fingers 4 and the pressure of the spring 9 on the fingers 4 is against the cam and serves to tighten the grip of the cam on the finger to insure a firm holding of the finger in any adjusted position.

It will readily be seen, however, that the fingers 4 may be pushed inwardly very easily by merely applying pressure against their outer ends 20, as such pressure will free the finger from the grip of the cam and permit the finger to be moved inwardly. As soon as inward pressure and movement of the finger stops, however, the cam 15 immediately grips the finger and holds it securely in the position it was adjusted to.

By this arrangement, it is possible to hold the template adjacent an object, such as an auto body, from which a contour impression is desired, with the tips or ends 20 of the fingers pointed toward the contour to be measured, and, by pressing the template inwardly toward the object, the finger tips 20 will engage the object. Continued inward pressure will push the fingers inwardly in their pockets or chambers 3 a predetermined distance in accordance with the relative engagement of the contour. (See Figs. 1 and 2.) The instant the inward movement of the fingers stops, they are clamped in that exact position by the cams 15 and the template may be removed from the object and the spaced tips 20 will indicate the contour of the object at the point the impression was made. The template or contour impression thus obtained may be used for any desired purpose, such as restoring a similar object which was dented to its original shape.

When the template has served its purpose, the fingers may be returned to their normal, outermost-extended position. This is accomplished

by a knob or wheel 21 carried on the shaft 22 which has a gear 23 thereon, as shown. The gear 23 engages a rack 24 formed on the longitudinal slide release bar 25 which extends the length of the body member and is reciprocable longitudinally therein. The slide release bar 25 has a plurality of spaced release lugs 26 extending therefrom, one adjacent each of the cams 15, and the cams each have a projection 27 thereon which is positioned opposite the lug 26 so as to be engageable thereby when the bar is moved. As may be readily seen from Figure 4, the rotation of knob 21 in the direction of the arrow 28 will cause the release bar 25 to move in the direction of the arrow 29, and each of the lugs 26 will engage the projections 27 of their respective adjacent cams and move the cam away from the finger it holds, thereby releasing the fingers to return to their outer or extended position. The device is thereby quickly made ready for re-use as desired.

It has been shown how all of the fingers may be set to a contour, or released, simultaneously. It is also desired to set or release the fingers individually. To permit individual setting of the fingers 4, I have provided a series of graduations 30 on the fingers. By providing these graduations, I make it possible to set my template from a table or chart which may be made up to indicate settings for adjacent fingers when a particular contour is desired. For example, for a given make and model of automobile, certain body contours at strategic points may be taken by my device and the settings of the fingers recorded in a table or chart so that one need not have a pattern from which to make his impression each time he uses the template. He may go to the chart or table and set each finger according to the graduations.

It will readily be seen that each of the fingers 4 may be set individually by merely applying inward pressure and movement thereto until the desired graduation setting is reached. In making such hand settings, it is possible that one might go beyond the proper setting before stopping the inward movement of a finger, and in order to eliminate the need for releasing all of the fingers and starting over again in such an event, I have provided an opening 31 above each cam 15 whereby a suitable tool or implement, such as a nail, screwdriver, or the like, may be inserted through the hole or opening 31 into the chamber 13 and engaged against the cam 15 to release its grip on the finger. Thereby, human errors are readily corrected most expeditiously.

As an additional feature, I have provided means whereby two or more units of my invention may be connected together in either longitudinally aligned or angular relation, whereby long or angularly related contours may be measured, see Figs. 1, 2, 3 and 6. This means comprises a hinge 32 having spaced parallel wing members 33-33 on each side thereof, the wing members preferably having their outer ends bent inwardly, as at 34, whereby they may be slid into the narrow channels 35 adjacent each end of each of the body members, as shown, to securely join two units together. Screws 36 or bolts may be used to further secure the units together if desired, of course.

Graduations 38 in degrees are preferably provided on the hinge 32, as shown, so that two adjacent units may be set in any desired angular relation, see Fig. 3, to obtain contour impressions.

which would not otherwise be obtainable in any degree of accuracy.

It is to be understood that I have herein shown and described one specific embodiment of my invention, and that my appended claims are not necessarily limited specifically thereto, but should be construed as broadly as permissible in view of the prior art.

Having thus described my invention, what I claim is:

1. A device for measuring contours comprising a body member, a plurality of spaced substantially aligned fingers reciprocably carried by said body, means biasing said fingers to normally extend in an outward position with one end thereof extending beyond said body, a cam mounted on said body adjacent each of said fingers, said cams being pivoted and biased in a position to normally engage said fingers and prevent outward movement of said fingers but to permit substantially free inward movement thereof, and means for releasing all of said cams simultaneously from engagement with their respective fingers.

2. A device for measuring contours comprising a body member, a plurality of spaced substantially aligned fingers reciprocably carried by said body, means biasing said fingers to normally extend in an outward position with one end thereof extending beyond said body, a cam mounted on said body adjacent each of said fingers, said cams

being pivoted and biased in a position to normally engage said fingers and prevent outward movement of said fingers but to permit substantially free inward movement thereof, and means for releasing all of said cams simultaneously from engagement with their respective fingers, said means comprising a release bar reciprocably mounted longitudinally of said body adjacent said cams, a lug extending from said bar adjacent and engageable with each of said cams, and means to reciprocate said bar whereby said lugs engage said cams substantially simultaneously to move the latter out of locking engagement with said fingers.
